UNITED STATES PATENT OFFICE

JAMES H. WAGENHORST, OF DETROIT, MICHIGAN

ARC LAMP

Application filed June 1, 1929. Serial No. 367,730.

My invention relates to improvements in arc lamps and has to do, more particularly, with the efficient control of the movable electrodes in a lamp employing two or more arcs and, further, with the construction of the reflector, within which the arcs are drawn, the housing enclosing the operating mechanism of the lamp and the means by which these parts are mounted.

10 Heretofore, in arc lamps having two or more arcs, it has been the practice to use a clutch for each of the movable electrodes and the result has been that, after the lamp has burned for sometime, the clutches do not act to feed or separate the carbons uniformly so that there is a variation in the length of the arcs and the light intensity. The principal object of my invention is to provide a means for controlling the movable electrodes, in a lamp having two or more arcs, which shall be effective so as to always cause a uniform separation of the electrodes so that all the arcs will be of uniform light intensity. A further object of my invention is to provide a single clutch controlling all of the movable electrodes and permitting relative adjustment of the movable electrodes with respect to each other, when the clutch is in releasing position.

25 A further object of my invention is to provide a simple, inexpensive but highly efficient arc lamp construction which will lend itself very readily to therapeutic uses.

30 A further object of my invention is to provide an arc lamp in which a central staff forms the backbone of the structure and supports the reflector and the housing for the lamp operating mechanism, which is carried on the top of the reflector.

35 Further objects, and objects relating to details and economies of construction and operation will definitely appear from the detailed description to follow. In one instance, I accomplish the objects of my invention by the devices and means set forth in the following specification. My invention is clearly defined and pointed out in the appended claims. A structure constituting a preferred embodiment of my invention is illustrated in the accompanying

drawings, forming a part of this specification, in which:

Figure 1 is a perspective view of an arc lamp embodying my invention, with the swinging front wall of the housing opened, 55

Fig. 2 is a central, vertical, sectional view through the lamp,

Fig. 3 is a transverse, vertical, sectional view through the lamp, the reflector hoods being moved to open position, 60

Fig. 4 is a horizontal, sectional view, taken on the line 4—4 of Fig. 2,

Fig. 5 is a horizontal, sectional view, taken on the line 5—5 of Fig. 2,

Fig. 6 is a detail, sectional view taken on 65 the line 6—6 of Fig. 2,

Fig. 7 is a fragmentary, sectional view showing the cooperation of the clutch and the control rods, the clutch being shown in releasing position in dotted lines, 70

Fig. 8 is a fragmentary plan view of the clutch with the control rods shown in section, and

Fig. 9 is a perspective view of the clutch member. 75

In the drawings, the same reference numerals refer to the same parts throughout the several views.

In general, my invention consists in providing a single clutch for controlling a 80 plurality of movable electrodes, which clutch, when in releasing position, permits relative movement of the electrodes. I propose to provide control rods with which the single clutch coacts, said control rods being 85 attached to the corresponding movable electrodes. For instance, electrode holders may be fastened to the upper ends of the movable electrodes and the control rods may be secured to said electrode holders. My invention further consists in providing a reflector which is mounted upon the upper end of a central staff and a housing mounted on top of the reflector and enclosing the operating mechanism of the lamp, the stationary electrodes being supported within the reflector by the staff, while the movable electrodes depend from the operating mechanism through the top wall of the reflector into alignment with the stationary electrodes. 95 100

The central supporting staff may well be tubular and this permits the control rods, which are centrally arranged, to be slideable in the upper end of the staff, thus making 5 for a more simple and compact structure.

Referring to the numbered parts of the drawings, in which I have illustrated a preferred embodiment of my invention, the central tubular staff 11 is mounted upon the 10 upper end of a standard 10. This staff 11 extends through the bottom wall of the reflector and the upper end thereof engages and is fastened to the top wall of the reflector. A nut 12 screwed on the lower end 15 of the staff 11 engages the outer face of the bottom wall of the reflector, so that the parts are held rigidly together. This nut 12 may also be screwed upon the upper end of the standard 10. Laterally-extending flanges 20 13 are provided on the upper end of the staff 11, by which that staff is attached to the top wall of the reflector. The reflector includes bottom, top and end walls, the sides 25 of the reflector being open, except as they may be closed by the hinged reflector hoods. The bottom wall is dished and comprises the central portion 14 and the upwardly inclined side and end portions 15. The end walls 16 extend upwardly from the upper edges of 30 the end portions 15 of the bottom wall and connect with the top wall 17. An inner sheet metal plate 18 is fastened to the top wall and has end portions 19 which extend downwardly parallel to the end walls 16, 35 but are spaced therefrom by means of the bolts 20 and the spacing washers 21. This provides a space between the end walls 16 and the end portions 19, within which the end members of the reflector hoods may 40 move. A reflector hood is hinged at each side of the reflector and each hood comprises the body portion 22 and the end members 23, which end members are adapted to move between the end walls 16 and the portions 19 45 of the reflector. The upper edge of the body 22 of each reflector hood is curved, as at 24, and hinged to the top of the reflector by means of the bolts 25. These reflector hoods may be opened, as shown in Fig. 3, in 50 order to divert the light coming from the arcs through the side openings of the reflector or one or both of these hoods may be swung to closed position, thus closing the side openings in the reflector. The edges 55 of the top wall 17 of the reflector are folded under the inner plate 18 and secured thereto, as shown at 26 in Fig. 3. A layer of asbestos board 27 is secured to the top wall 17 by the bolts 28, and forms the bottom of 60 the housing mounted upon the top of the reflector. The reflector is fastened to the upper end of the central staff 11 by the bolts 29 extending through the flanges 13 and through the top wall of the reflector and 65 the asbestos board 27.

The housing mounted upon the top of the reflector comprises end walls 30 and a fixed side wall 31. The lower portions of said side and end walls are bent inwardly, at 32, beneath the asbestos board 27, and the bolts 70 28 pass through these inturned flanges, thereby securing the housing in position on the top of the reflector. Both the side and end walls of the housing are provided with a plurality of louvers 33, which admit air, permitting it to circulate through the housing for the purpose of cooling the operating mechanism of the lamp. Opposite the fixed side wall 31 of the housing, there is a hinged side wall 34, also provided with louvers 33, having an inturned stiffening flange 36. This side wall 34 is hinged at the bottom of the housing by means of the bolts 35. The upper portion of the fixed side wall 31 is inclined forwardly, at 37, while the upper portions of the end walls 30 are inclined toward each other, at 38, as shown in Fig. 2. The swinging side wall has a correspondingly inclined upper portion 39. A bracket 40 is secured to the fixed side wall 31 by the bolts 41. This bracket has a portion 42 which extends across the open top of the housing and carries an eye 43 by means of which the apparatus may be suspended, if it is desired to remove the staff 11 from the standard 10 and suspend the lamp. The forward portion 44 of the bracket is bent downwardly, as shown in Fig. 3, and has a slot 45 receiving a fastening bolt 46. The nut upon this bolt can be backed up and, when the swinging side wall is moved to closed position, the bolt 46 will be received in a notch 47 in the upper edge thereof. The nut 46 can then be turned down to fasten the swinging side wall in closed position. 100

A pair of stationary electrodes 48 are supported by the central staff 11 within the reflector, these electrodes being located one on each side of the central staff. These stationary electrodes are so supported from the central staff that they are insulated from each other, and from the central staff, by the clamping members, best shown in Fig. 5. The support for the stationary electrodes 110 comprises a pair of clamping members 49, having half-round portions at one end adapted to embrace the central staff and smaller half-round portions at the opposite end to embrace one of the stationary electrodes. A strip 50 of insulating material is interposed between the staff 11 and the clamping members 49. Similar clamping members 51 are provided which have half-round portions at one end adapted to embrace the adjacent portions of the clamping members 49, and curved portions at the other end to embrace the corresponding stationary electrode 48. A strip 52 of insulating material is interposed between the 115 120 125 130

clamping members 51 and the clamping members 49. These clamping members are all secured together by means of the bolts 53, which clamp them rigidly in position 5 upon the central staff. The stationary electrodes may be clamped in the outer ends of these clamping members by the bolts 54, which are provided with thumb nuts and also constitute terminals to which the circuit 10 wires are connected. Blocks 76 of insulating material are fastened to the bottom wall of the reflector, thereby preventing short-circuiting through the reflector in case the electrodes should be displaced.

15 The movable electrodes 55 extend from the housing through the holes 56, formed in the asbestos board 27 and the top wall of the reflector, in alignment with the stationary electrodes 48. Plates 57 are secured to the 20 top of the asbestos panel 27 and have openings in line with the holes 56 through which the movable electrodes 55 pass. An electrode holder is fastened to the upper end of each of the movable electrodes 55 and extends laterally therefrom toward the center 25 of the housing. Each of these electrode holders comprises a pair of clamping members 58 (see Fig. 6), having at one end the half-round portions 59 adapted to embrace 30 the movable electrode 55, and, at the other end, the squared portions 60 adapted to be clamped about a squared rod 61. The electrode holder, however, is insulated from the squared rod 61 by the strip of insulation 62 35 interposed between the clamping members 58 and said rod 61. The clamping members 58 are clamped about the rod 61 by the bolts 63, and may be clamped about the electrode 55 by the bolt 64, which serves also as a 40 terminal for the circuit wire connected thereto.

45 A control rod 65 is provided for each of the movable electrodes. These control rods are arranged side by side, as shown in Fig. 2, and with their lower ends slidably mounted in the upper portion of the central tubular staff 11, said rods extending downwardly through a hole 66 formed in the top wall of the reflector. The legs of a staple 50 67 are inserted through the staff 11 on opposite sides of the rods 65, so as to prevent tilting and displacement of the rods in said staff. These rods should be of such size with respect to the tubular staff and 55 each other that they will move freely and will not bind or stick. The squared rod 61 is U-shaped and has one leg driven into the upper end of the corresponding tubular control rod 65, whereby said squared rod is 60 rigidly fastened to the control rod and becomes, in effect, a part thereof. The opposite leg of this U-shaped squared rod is clamped in the electrode holder as already described. By this means the control rod 65 is rigidly attached to the corresponding

movable electrode 55 so that it extends parallel thereto.

I provide a single clutch co-acting with the control rods 65 to control both of the movable electrodes 55. This clutch member 70 75 has an elongated opening 69 through which the control rods 65 pass, there being smaller offset notches 70 at each end of the large elongated opening 69, as shown in Fig. 8. When this clutch is in the dotted 75 line position, shown in Fig. 7, the control rods 65 are free to move longitudinally through the clutch member and relative to each other. When, however, the clutch is tilted, as shown in full lines in Fig. 7, it 80 will grip the two control rods, hold them against movement relative to each other, and permit them to be lifted by the clutch member. The clutch operating link 71 has its lower end turned laterally, at 72, and 85 inserted in a bore 73 formed in the end of the clutch member. The removal of the end of the link from this bore is prevented by the pin 74, inserted transversely through the clutch and engaging the groove 75 in 90 the end portion 72 of the link. The upper end of this link is connected to the clutch operating mechanism.

The operating solenoid 79 is supported from one end wall of the housing by means 95 of the spring supports 78, which are carried by the blocks 77 fastened to that end wall. The solenoid core 80 is connected by a spring 81 to one arm of the U-shaped operating lever 82. This lever is pivoted on the pin 83 carried by the bracket 40. An eye 84 formed in the upper end of the link 71 is hooked through a hole 85 in the opposite end of this operating lever. A dash pot 86 is suspended from the same arm of 100 the lever and a plunger 88 works in this dash pot. This plunger is carried on the upper end of a plunger rod 87 which is fastened to the top of the reflector and extends upwardly therefrom. A slab of insulating material, such as asbestos board, 105 is fastened to the top of the reflector and extends upwardly within the housing but spaced from one end wall thereof so as to form a chamber with said end wall. This slab of insulating material is secured in place by the bracket 90 which is fastened to the top of the reflector, and held in spaced relation from the end wall by the bolt 91 and the spacing sleeve 92 at the upper end 110 thereof. In the chamber thus formed between the end wall and the slab, the resistance coils 93 are mounted upon the slab 89. It will be seen that the upper end of this chamber is open and air will enter through 115 the louvers 33, in the end wall and the adjacent portions of the side walls, and this current of air will pass upwardly over the resistance coils and out through the open 120 top of the housing. This arrangement aids 125 130

materially in keeping these coils from overheating.

The operating current is brought through the main wires 94 to the main control switch 95 mounted on the bottom of the reflector. From this switch, one wire 96 leads to the terminal for the left-hand lower electrode 48 in Fig. 2. From this electrode the current passes to the corresponding movable electrode 55. From the electrode holder attached to the upper end of this movable electrode, the current passes through the wire 97 to the upper end of the solenoid 79, and from the lower end of said solenoid 15 through the wire 98 to the terminal 99 at one end of the resistance coil 93. From the terminal 100, at the other end of said resistance coil, the current passes through wire 101 to the electrode holder fastened 20 to the upper end of the right-hand movable electrode, as shown in Fig. 2, and, thence, through this electrode and the corresponding stationary electrode 48 and the wire 102 back to the switch. It will be seen that the 25 two pairs of electrodes, the solenoid and the resistance coils are all connected in series.

From the description of the parts given above the operation of this arc lamp should be very readily understood. In Fig. 2, the 30 electrodes are shown in the position they occupy when both arcs have been drawn and are in operation. If either arc should be extinguished, or the circuit should be interrupted for any reason, the solenoid 79 35 being de-energized will permit the core 80 to rise, thus permitting the opposite end of the operating lever 82 to drop and the clutch 68 to drop to its releasing position. As soon as this happens, the control rods 40 65 will be released and the weight of these rods and the electrodes connected thereto will cause these parts to move downwardly until the movable electrodes 55 contact with the upper ends of the stationary electrodes 48, whereupon the circuit will be re-established, the solenoid energized once more, the clutch lifted to grip the control rods and draw both arcs simultaneously, effecting an 45 equal separation of the electrodes since both the upper electrodes are moved together. If, for any reason, one electrode should burn away more rapidly than the other, there will be a relative movement of the control rods and the connected electrodes with 50 respect to each other when the clutch is in releasing position, thus compensating for the difference in the rate at which the electrodes are consumed, so that, when the arcs are next formed, the electrodes will again 55 be separated an equal amount. This means that the arcs are always of the same light intensity and this results in a much more efficient and effective working of the lamp. Furthermore, as the electrodes burn away 60 and the arcs are thus gradually lengthened,

the resistance in the circuit gradually increases, thus decreasing the pull of the solenoid 79 upon core 80 and gradually lowering link 71 until clutch 68 engages plate 27. When this happens the clutch tilts sufficiently to release the control rods 65 and they are lowered simultaneously a slight distance, decreasing the length of the arcs and the resistance so that the pull of the solenoid on its core is slightly increased to 70 lift the clutch from engagement with plate 27 causing it to tilt and clutch the control rods once more. Thus the electrodes will be fed by small successive increments, simultaneously, maintaining the arcs substantially 75 constant without breaking the circuit. The control rods having been forced tightly against each other by the clutch, will descend simultaneously as one unit when the clutch touches plate 27 and releases, but if the rods 80 drop until upper and lower electrodes contact, relative movement of the control rods may then take place until both pairs of electrodes contact.

It will be observed that the central staff 90 11 constitutes the backbone of the lamp, the reflector being mounted upon this and the operating mechanism being carried by the housing which is mounted on top of the reflector. Furthermore, the reflector hoods 95 are hinged to the reflector and adapted to close the side openings thereof and may be opened so that the light from the arcs may be directed at one side or both as required.

I am aware that the particular construction illustrated in this application may be changed considerably, without departing from the spirit of my invention, and, therefore, I claim my invention broadly, as indicated by the appended claims.

What I claim is:

1. In an arc lamp, the combination of a pair of stationary electrodes, a pair of movable electrodes having rod-like portions constituting extensions thereof, a single clutch 100 coacting with said rod-like extensions and means for actuating said clutch.

2. In an arc lamp, the combination of a plurality of stationary electrodes, a plurality of electrodes independently movable 115 with respect to each other and cooperating with said stationary electrodes to provide a plurality of arcs, a single clutch restraining said movable electrodes as a unit, means providing partial release of said clutch and effecting equal feeding of said movable electrodes when the current passing through the arcs is decreased due to electrode consumption and providing complete release of said clutch and permitting differential movement 120 of said electrodes when the current is interrupted.

3. In an arc lamp, the combination of a pair of stationary electrodes, a pair of movable electrodes cooperating therewith, a con- 125

trol rod attached to each of said movable electrodes, a single clutch co-acting with said control rods, and means for actuating said clutch.

5. In an arc lamp, the combination of a pair of stationary electrodes, a pair of movable electrodes cooperating therewith, a control rod fastened to each movable electrode, said control rods being longitudinally movable relative to each other, a single clutch co-acting with said control rods, and means for actuating said clutch.

10. In an arc lamp, the combination of a pair of spaced stationary electrodes, a pair of movable electrodes cooperating therewith, a control rod fastened to each movable electrode, said control rods being arranged side by side and longitudinally movable with respect to each other, a single clutch co-acting with both of said control rods, and means for actuating said clutch.

15. In an arc lamp, the combination of a pair of stationary electrodes, a pair of movable electrodes cooperating therewith, electrode holders fastened to the upper ends of said movable electrodes, a pair of relatively shiftable control rods secured to said electrode holders, a single clutch co-acting with said control rods, and means for actuating said clutch.

20. In an arc lamp, the combination of a pair of spaced stationary electrodes, a pair of movable electrodes cooperating therewith, an electrode holder secured to the upper end 25 of each movable electrode and extending laterally therefrom, control rods centrally arranged and carried by said electrode holders, a single clutch co-acting with said control rods, and means for actuating said clutch.

25. In an arc lamp, the combination of a pair of stationary electrodes, a pair of movable electrodes cooperating therewith to draw a pair of arcs simultaneously, a single clutch controlling said movable electrodes and permitting independent movement thereof when in releasing position, and means for actuating said clutch.

30. In an arc lamp, the combination of a pair of stationary electrodes, a pair of movable electrodes cooperating therewith, electrode holders clamped about the upper ends of said movable electrodes and extending laterally therefrom, a pair of tubes arranged 35 side by side, U-shaped rods each having one leg fixed in the upper end of one of said tubes and the other leg secured to one of said electrode holders, a single clutch co-acting with said tubes, and means for actuating said clutch.

35. In an arc lamp, the combination of a pair of stationary electrodes, a pair of movable electrodes cooperating therewith to draw a pair of arcs simultaneously, a single clutch controlling both movable electrodes

and permitting relative movement thereof when in releasing position, a clutch-operating solenoid, an armature therefor, and operating connections between said clutch and armature. 70

40. In an arc lamp, the combination of a pair of stationary electrodes, a pair of movable electrodes cooperating therewith, a control rod fastened to each of said movable electrodes, a single clutch co-acting with both of said rods, a clutch-operating solenoid, an armature therefor, and operating connections between said armature and clutch. 75

45. In an arc lamp, the combination of a central staff, a reflector mounted on the upper end of said staff, a housing mounted on top of said reflector, a stationary electrode supported by said staff within the reflector, electrode-operating mechanism enclosed within said housing, and a movable electrode depending therefrom into the reflector and cooperating with the stationary electrode. 80

50. In an arc lamp, the combination of a central staff, a reflector mounted on the upper end of said staff, a housing mounted on top of said reflector, a pair of stationary electrodes supported by said staff on opposite sides thereof within the reflector, electrode operating mechanism enclosed within said housing, and a pair of movable electrodes depending therefrom into the reflector in alignment with the stationary electrodes. 85

55. In an arc lamp, the combination of a central staff, a reflector mounted on the upper end thereof, a housing mounted on top of said reflector, a pair of stationary electrodes supported by said staff within said reflector, electrode-operating mechanism carried by said housing, and a pair of movable electrodes depending therefrom, through holes in the top wall of said reflector, into cooperative relation with said stationary electrodes. 90

60. In an arc lamp, the combination of a central staff, a reflector mounted on the upper end thereof, a housing mounted on top of said reflector, a stationary electrode supported by said staff within the reflector, a solenoid supported by the housing, a movable electrode extending through the top wall of said reflector into alignment with the stationary electrode, a clutch controlling the movable electrode, a core for said solenoid, and operating connections between said clutch and core. 115

65. In an arc lamp, the combination of a central staff, a reflector mounted on the upper end thereof, a housing mounted on top of said reflector, a stationary electrode supported by said staff within the reflector, a solenoid carried by said housing, a movable electrode extending through a hole in the 120

- top of said reflector into cooperative relation with said stationary electrode, a clutch controlling the movable electrode, a lever pivoted on said housing, a core for said solenoid connected to one arm of said lever, and a link connecting the opposite arm of said lever and the clutch. 5
17. In an arc lamp, the combination of a central staff, a reflector mounted on the upper end thereof, a housing mounted on top of said reflector, a stationary electrode supported by said staff within said reflector, a movable electrode extending through the top of said reflector into cooperative relation 10 with said stationary electrode, a clutch controlling said movable electrode, a solenoid carried by said housing, a lever pivoted on said housing, a core for said solenoid connected to one arm of said lever, connections 15 between said lever and clutch, a dash-pot suspended from said lever, a plunger rod mounted on the top of said reflector, and a plunger on the upper end of said rod working in said dash-pot. 20
18. In an arc lamp, the combination of a central staff, a reflector mounted on the upper end thereof, a housing mounted on top of said reflector, cooperating electrodes, electrode-operating mechanism enclosed within 25 said housing, a panel mounted on the top of the reflector and extending upwardly within the housing in spaced relation to an end wall thereof, and a resistance coil connected in series with said electrodes and mounted on said panel in the chamber formed thereby, 30 said coil being separated from the operating mechanism by said panel. 35
19. In an arc lamp, the combination of a central tubular shaft, a reflector mounted on the upper end thereof, a pair of stationary electrodes supported by said staff within said reflector, a pair of movable electrodes extending through the top wall of the reflector into cooperative relation with the 40 stationary electrodes, control rods fastened to the movable electrodes and extending into the tubular staff, a single clutch co-acting with said control rods, and means for actuating said clutch. 45
20. In an arc lamp, the combination of a central tubular staff, a reflector mounted on the upper end thereof, a pair of stationary electrodes supported by said staff on opposite sides thereof within the reflector, a 50 pair of movable electrodes extending through the top of said reflector in alignment with the stationary electrodes, electrode holders fixed to the movable electrodes and extending laterally therefrom, a pair of 55 control rods secured to the electrode holders and slidably mounted in the upper end of said staff, a single clutch positioned above the top wall of the reflector and engaging both control rods, and means for actuating 60 said clutch. 65
21. In an arc lamp, the combination of a central tubular staff, a reflector mounted on the upper end thereof, a housing mounted on top of the reflector, a pair of stationary electrodes supported by the staff within the reflector, a pair of movable electrodes extending through the top of said reflector in alignment with the stationary electrodes, electrodes holders fastened to the movable electrodes and extending laterally from the upper ends thereof, a pair of control rods secured to said holders and depending therefrom into the upper end of said staff, a single clutch engaging said rods, a clutch-operating solenoid mounted on said housing, 70 a core therefor, and connections between the clutch and core. 75
22. In an arc lamp, the combination of a reflector having side openings, reflector hoods hinged to the top of the reflector and adapted to close said side openings, and a housing mounted on top of said reflector. 80
23. In an arc lamp, the combination of a reflector having a dished bottom and side openings, reflector hoods hinged to the top of said reflector and adapted to close the side openings, and a housing mounted on top of the reflector. 85
24. In an arc lamp, the combination of a reflector having side openings, reflector hoods hinged to the top of the reflector and adapted to close said openings, and a housing mounted on the top of the reflector and having a swinging side wall. 90
25. In an arc lamp, the combination of a reflector having rigid top and bottom walls, and a support for the reflector comprising a central staff extending snugly through the bottom wall and secured to and supporting the reflector from its top wall. 95
26. In an arc lamp, the combination of a reflector having rigid top and bottom walls, and a combined brace and support for the reflector comprising a central tubular staff extending through the bottom wall, secured to and supporting the top wall, and a sleeve mounted about the tubular staff and snugly engaging the outer face of the bottom wall. 100
27. In an arc lamp, the combination of a pair of spaced stationary electrodes, a pair of movable electrodes cooperating therewith, a control rod fastened to each movable electrode, said control rods being arranged side by side, a single clutch bringing the rods tightly together for movement as a unit when engaged thereby, and allowing relative longitudinal movement of the rods when released, and means for actuating the clutch. 105
